UNITED STATES PATENT OFFICE.

HORACE M. EATON, OF NAWANT, MASSACHUSETTS, ASSIGNOR OF ONE-HALF TO
GEORGE L. PREBLE, OF LYNN, MASSACHUSETTS.

MACHINE FOR CASTING TENSION UPON FABRICS.

Application filed January 11, 1928. Serial No. 245,980.

This invention relates to a machine for casting tension upon a flexible strip and more specifically to a machine adapted to assist in the manufacture of insoles for welt shoes.

5 In some respects the present machine comprises an improvement over that disclosed in my copending application Serial No. 225,718, filed October 12, 1927.

My copending application Serial No. 10 214,229, filed August 20, 1927, discloses a new method of manufacturing reinforced insoles, wherein reinforcing fabric is provided with a permanently plastic, tenaciously adhesive agglutinant that may be applied directly to the leather insole without requiring heating or any preliminary treatment. Prior to my aforesaid improvement in insole manufacture, because of the necessity of running the duck or canvas through a 20 heater, it was impractical to provide insole reinforcing fabric in various widths in order instantly to change from the use of fabric of one width to the use of fabric of another width during the course of manufacture. 25 Since the heater is eliminated by the aforesaid invention, it is now feasible to use reinforcing strips of various widths to suit various sizes of insoles, thus avoiding unnecessary loss of fabric and affording greater 30 economies in shoe manufacture. While the adhesiveness of the plastic coating may be varied, it is highly desirable and practicable to provide an agglutinant which has strong adhesion; with material of this character 35 considerable force is required to draw the run of coated fabric from a roll of the same, due to the firm adhesion existing between the fabric windings.

The machine presented herewith is primarily arranged to permit the use of duck or canvas of this character which is highly adhesive and yet to avoid unnecessary tiring of the workman who is applying the reinforcing fabric to the insoles, while permitting the ready, interchangeable use of various types of insole fabrics (e. g. different widths to suit different widths of insoles). This mechanism is designed to be immediately responsive to a light pull upon the 45 part of the operator, so that the use of the improved reinforcing fabric in conjunction with the machine requires less effort upon the part of the workman than has previously been necessary. Thus the present invention permits the workman to take hold 50 of the severed end of any one of several fabric strips and to draw the same lightly, whereupon the machine automatically will start operation in order to cast suitable additional tension upon the fabric run that extends from the adhesively coated roll, thereby overcoming the effect of the strong adhesion between the windings of the roll. The machine is designed to be compactly installed beneath the work-bench that is commonly used in applying the fabric to the insoles so that it will not require additional floor space, or it may be an integral part of a specially constructed bench to be used for this purpose. 55

One aspect of the present invention particularly relates to the provision of improved means permitting the instant change from the use of one type of fabric to a fabric having a different width or different characteristics. Means are provided whereby the interchangeable use of the various fabric strips does not affect the adjoining strips which are not being used. In order to cast additional tension upon the coated strip, it 60 is desirable to utilize a friction roll, a portion of which engages the fabric run. A further aspect of the invention concerns the provision of means designed to prevent the continued movement of the fabric after the 65 tension cast thereon by the operator is relieved. In other words, the frictional means which are found effective in casting additional tension upon the fabric has a certain momentum or inertia which tends to cause 70 their continued movement after the driving energy provided therefor has ceased, and the present invention provides means normally holding the fabric out of engagement with the friction roll, except when tension is being 75 cast upon the same by the workman, so that rotation of the roll in order to feed another strip of fabric to the point of use, or rotation of the roll due to the inertia of the rotating parts, is not permitted to affect the 80 strips which are engaged by this factor. Means of this character may be adjusted and 85 may also cooperate in effecting the automatic stopping of the machine when the initial tension from the hand of the operator 90 ceases. 95

The above and further advantageous features of the invention will be apparent to those skilled in the art upon a reading of the subjoined description and claims in con- 100

105

110

junction with the accompanying drawings, in which:

Fig. 1 is a side elevational view of one embodiment of the machine forming the subject matter of this invention;

Fig. 2 is a top plan view of the same; and

Fig. 3 is a section on line 3—3 of Fig. 2 showing the parts in another position.

10 A machine of the type exemplified in the accompanying drawings preferably is supported upon the end portion of a work-bench or table 2 of a type that may be used in applying the reinforcing fabric to the insoles. Thus the machine does not require the use of additional floor space. For the purposes of this invention the table 2 is provided with a peripheral frame 1 of angle iron. The wooden top of the table has one 15 corner cut away in order to provide a rectangular opening 4 within the corner of the angle iron frame 1.

20 Suitable hangers 5 are secured to the under face of table 2, each of these hangers carrying a horizontal spindle 6 upon which a roll 8 of the adhesively coated fabric is located. Preferably the spindles 6 are provided with conventional retaining elements 7 and washers 11 in order to permit the 25 ready removal, replacement, and retention of the rolls as desired. Each of the fabric rolls 8 preferably comprises duck or canvas coated with a permanently plastic, tenaciously adhesive agglutinant with the adhesive coating upon the inner face of each 30 winding firmly holding the same in engagement with the outer uncoated face of the adjoining winding. Preferably the fabric in each of the rolls 8 may differ in width or 35 any other characteristics from the fabric of the other rolls so that any one of the fabric runs may be selected and utilized for reinforcing insoles without necessity of delay while changing from one type of fabric 40 to another.

45 A horizontal shaft 21 forming the extension of the axle of worm gear 37 carries a plurality of friction rolls 20; these may have widths substantially corresponding to the 50 various widths of strips, as shown in Fig. 2. Each of these rolls preferably has a peripheral covering 24 of material having a comparatively high coefficient of friction, for 55 example soft rubber, and is so arranged that a run of fabric from one of the fabric rolls 8 may be wrapped about a considerable segmental portion of its periphery when the 60 fabric is fed to the point of use, whereby the friction roll may have an effective frictional engagement with the fabric strip. Pivottally mounted upon the shaft 21 are a 65 plurality of swinging yokes or frames 27 which have arms projecting upwardly through opening 4. The frame 1 and the 70 wall of the opening 4 which is formed by

the wooden table top form stops to limit the swinging movement of frames 27. The sides of each frame support a transverse roller 28 therebetween at their upper extremities, this roller being adapted to receive one of the fabric runs as it leaves the roll 20 and cooperating with the same in effecting the engagement of the uncoated fabric surface with a considerable peripheral portion thereof, while permitting the strip to be drawn in the general direction of the surface of table 2 by the workman. The lower portion of the frame 27 is extended to provide guards 30 which may be located at either side of the periphery of so a roller 20 in order to prevent undesirable lateral movement of the fabric.

75 A suitable electric motor 35 is arranged to rotate shaft 21 and rollers 20 in order to cast the desired tension upon a fabric strip 80 leaving a roll 8. This motor may drive the shaft through any suitable means, such as the worm 36 and the worm gear 37. Preferably motor 35 is energized through an 85 electrical line that is controlled by a conventional switch factor 38 such, for example, as a suitably enclosed mercury switch. The switch is operated by an oscillatable link 39, the end of which is pivotally connected to a swinging frame 40, the upper end of which is provided with pintles 41 supported by suitable brackets secured to the 90 table, while the lower part of member 40 comprises a transverse element which is positioned so that it lies within the path of 95 each of the swinging frames 27, Figs. 1 and 3.

100 Secured to the under surface of table 2 is the transverse angle 50. A plurality of loops 51 of comparatively heavy, resilient wire 105 have their ends clamped to the depending leg of member 50 by a bar 52 and fastening elements 53; it being evident that means of this character permits the relative adjustment of the loops and angle member. Each 110 wire loop preferably extends downwardly about the lower half of the friction roll 20 and is passed through an opening in a transverse bar 55 in each of the frames 27. The 115 ends of the wire loops are looped over another transverse bar 57 upon frame 27, as shown in Figs. 1 and 3, the relative position of bars 55 and 57 permitting each wire loop to engage substantially one-half of the periphery of a friction roll. The roll portions preferably are provided with suitable 120 peripheral grooves 56 registering with the wire loops 51 and having a depth greater than the diameter of the wire of these loops. The present disclosure shows two grooves 125 and two wire loops for each roller portion, but it is to be understood that the number of these elements may be varied if desired.

130 When the frame 27 is swung to a position wherein its upper end engages the angle 1

as a stop, Fig. 1, the resilient wire loops 51 are moved to their unretracted position wherein they are located somewhat outwardly of the periphery of the frictional roll portions. At the same time the switch 38 is open and the member 40 is swung toward the frame 27. When any of the several frames 27 is swung upwardly so that the edge of the wooden table top acts as a stop therefore, the intermediate portion of the frame is engaged against the transverse part of switch control member 40 and holds the link 39 in a position ensuring the closing of the electrical circuit, at the same time the wire loops 51 are drawn into their retracted positions within the peripheral grooves so that their outer surfaces lie below the rubber faces of the rollers.

In the use of a machine of this character, the fabric run from each roll is fed under the corresponding friction roll, its uncoated surface being ordinarily engaged with the wire loops 51 which, in their unretracted position, are disposed somewhat outwardly of the periphery of the friction roll portions, as shown in Fig. 1. The fabric then passes over roller 28, the end thereof being located upon the top of table 2 within convenient reach of the hands of the machine's operator. Thus, when the machine is not being actually operated, a plurality of fabric ends will be located side by side at one edge of the table top ready to be selected and lightly pulled by the workman; and, while in this position, the strips may be gripped between the frames 27 and frame member 2, as shown in Fig. 1. This pulling of the fabric strip results in the swinging of member 27 against the action of spring elements 51 to the position which is shown in Fig. 3. Thus these elements are brought to their retracted positions within the particular roll about which the pulled fabric is wrapped. Thus the selected fabric strip which previously was held out of engagement with the friction roll by the wire elements 51 is brought into firm engagement with the same. At the same time the element 27 engages switch control member 40 to swing the latter through a path which results in its actuating link 39 to close the switch and to start the electric motor 35. This driving means rotates shaft 21 through gearing 35 and 36, thus causing the rotation of each of the friction rollers and the consequent imparting of additional tension to the selected fabric run as it leaves the roll 8. In the meantime the elements 51 for the adjoining strips of fabric which are not being pulled by the operator remain in their unretracted positions and hold these strips out of engagement with the adjoining portions of the friction rollers so that operation of the machine has no effect upon the fabric strips which are not being pulled by the operator. As soon as the pull upon the end

of the strip is released, the frame 27 will swing back to its normal inoperative position under the influence of spring members 51, thus releasing switch members 38 and 40, opening the electrical circuit and stopping the provision of driving energy to the machine. At the same time the spring elements 51 are moved outwardly from their retracted positions and remove the fabric strip from its position in engagement with the periphery of the frictional roll so that continued movement of this roll due to the momentum of the rotating parts will not result in further movement of the fabric. This latter function is desirable, since, after the pull of the operator upon the fabric strip ceases, continued movement of the portion of the strip which adjoins the roll might result in the uncoated face of the strip continuing in engagement with the periphery of the roll and wrapping entirely about the same so that the end of the strip could no longer be conveniently reached by the operator of the machine.

It is evident that with a machine of this character the operator need use only a light pull in order to draw any of the selected strips from its roll in order to provide a sufficient length thereof for reinforcing one or more insoles and that the release of the tension which he casts upon the strip will instantly result in the cessation of the tension which is imparted to the run by the friction drum 20. Obviously the use of the narrowest fabric practical for the insoles being manufactured permits a distinct economy in the use of material, while it is also sometimes desirable to use reinforcing fabrics of different weights for different types of shoes without any delay due to the change from one type of fabric to another. It is further evident that the operator may immediately change from the use of reinforcing fabric of one width or type to that of another width or type without any necessity for delay due to such a change.

I claim:

1. Apparatus for pulling a run of adhesively coated material from a roll of said material, comprising an element adapted frictionally to engage the run of material, means to impart movement to said element, control means for said last-named means, said control means being actuated by initial tension cast upon said run in order to draw the run from the roll, and means to move the fabric from engagement with the friction element when the control means is released due to a slackening of the tension upon the fabric run.

2. Apparatus for pulling a run of adhesively coated material from a roll of said material, comprising a friction roll element adapted to engage a run of material, means to impart movement to said friction

element, a plurality of rolls of coated material arranged so that a run of said material may engage a segmental surface of the friction roll element, and means permitting the selective engagement of one of said runs without causing engagement of the others with said element.

3. Apparatus for pulling a run of adhesively coated material from a roll of said material, comprising a plurality of friction rolls, means to impart movement to said friction rolls, means for supporting a plurality of rolls of coated material arranged so that a run of said material may engage a segmental surface of a friction roll, and means permitting the selective engagement of one of said runs with a friction roll without causing engagement of the others with a roll, said means including grooves in the peripheries of the friction rolls and parts movable from a retracted position in the grooves to a position wherein they are disposed radially outward in relation to the grooves.

4. Apparatus for pulling a run of adhesively coated material from a roll of said material, comprising friction rolls, means to impart movement to said friction rolls, means for supporting a plurality of rolls of coated material arranged so that a run of said material may engage a segmental surface of a friction roll, and means permitting the selective engagement by a friction roll of one of said runs without causing engagement of the others with a roll, said means including grooves in the peripheries of the friction roll and resilient loops movable from a retracted position in the grooves to a position wherein they are disposed radially outward in relation to the grooves.

5. A machine of the class described, comprising means for supporting a plurality of replaceable rolls of fabric having one face adhesively coated, the supporting means permitting free rotation of each roll, a friction roll element, a plurality of movable frames, said roll element and each frame having surfaces adapted to engage the uncoated face of a run of fabric extending from a fabric roll, each frame being movable in response to initial tension cast upon the corresponding run, driving means for imparting movement to said friction roll element, and common control means actuatable by the movement of any of said frames to control the operation of said driving means.

6. A machine of the class described, comprising means for supporting a plurality of replaceable rolls of fabric having one face adhesively coated, the supporting means permitting free rotation of each roll, a friction roll element, a plurality of movable frames, said element and each frame having surfaces adapted to engage the un-

coated face of a run of fabric extending from a replaceable roll, each frame being movable in response to tension cast upon the corresponding run, electrical driving means for imparting movement to said friction roll element, and an electrical switch actuatable by the movement of each frame to control the operation of said driving means.

7. Mechanism to assist in imparting tension to a flexible strip, comprising a friction roll arranged to engage the strip, driving means for the roll, an electric switch controlling said driving means, control means engageable by the strip when initial tension is cast thereon to close said switch so to cause operation of the driving means and the impartation of additional tension by the frictional roll and said control means being automatically actuated upon the termination of said initial tension to permit stopping of the driving means, and a factor operable immediately upon the termination of said tension to remove the strip from engagement with the roll while the latter may continue to rotate due to inertia.

8. Apparatus for pulling a run of adhesively coated fabric from any one of a plurality of rolls of said fabric, comprising a friction roll adapted frictionally to engage each fabric run, driving means to rotate each friction roll, a plurality of swinging frames each adapted to be engaged by a run of the fabric as it leaves a friction roll and to swing in response to tension cast upon said run, control means actuatable by the movement of a swinging frame in order to start and stop the driving means, and means to engage each of the runs upon which tension is not cast in order to hold these runs out of engagement with the friction roll.

9. Apparatus for pulling a run of adhesively coated fabric from any one of a plurality of rolls of said fabric, comprising a friction roll adapted to engage each fabric run, driving means to rotate said friction rolls, a plurality of swinging frames each adapted to be engaged by a run of the fabric as it leaves a friction roll and to swing in response to tension cast upon said run, control means actuatable by the movement of a swinging frame in order to start and stop the driving means, and means to engage each of the runs upon which tension is not cast in order to hold these runs out of engagement with the friction roll and to disengage the run from the roll as soon as the control means is actuated to stop the driving means, thus preventing further movement of the run due to the inertia of the driving means or the friction roll.

10. Apparatus for pulling a run of adhesively coated fabric from any one of a plurality of rolls of said fabric, comprising a friction roll adapted frictionally to engage each fabric run, driving means to rotate

said friction rolls, a plurality of swinging frames each adapted to be engaged by a run of the fabric as it leaves a friction roll and to swing in response to tension cast upon said run, control means actuatable by the movement of a swinging frame in order to start and stop the driving means, and means to permit the effective engagement of the friction roll with any selected run of material without engaging the others, said last-named means being controlled by the swinging frames.

11. A machine of the class described, comprising means for supporting a plurality of replaceable rolls of fabric having one face adhesively coated, the supporting means permitting free rotation of each roll, a plurality of friction rolls rotatable together, a plurality of movable frames, each friction roll and frame having a surface adapted to engage the uncoated face of a run of fabric extending from a fabric roll, each frame being movable in response to initial tension cast upon the corresponding run, driving means for imparting movement to said friction roll element, and common control means actuatable by the movement of any of said frames in one direction to cause the operation of said driving means.

30 12. Apparatus for pulling a run of adhesively coated fabric from any one of a plurality of rolls of said fabric, comprising a plurality of friction rolls each adapted frictionally to engage a fabric run, driving means to rotate said friction rolls, a plurality of swinging frames each adapted to be engaged by a run of the fabric as it leaves a friction roll and to swing in response to tension cast upon said run, control means actuatable by the movement of a swinging frame in order to start and stop the driving means, resilient loops tending to move the frames from the position which they occupy when they are actuating the control means in order to run the driving means, grooves in said friction rolls, said loops occupying a retracted position within the grooves when the corresponding frame is swung from said position and occupying a position outwardly of the peripheries of said rolls when the frame is in said position, whereby they permit engagement of the fabric run with the roll only when the corresponding frame is causing operation of the driving means.

60 13. Apparatus for pulling a run of adhesively coated fabric from any one of a plurality of rolls of said fabric, comprising a plurality of friction rolls each adapted frictionally to engage a fabric run, driving means to rotate said friction rolls, a plurality of swinging frames each adapted to be engaged by a run of the fabric as it leaves a friction roll and to swing in response to tension cast upon said run, control means

actuable by the movement of a swinging frame in order to start and stop the driving means, resilient loops tending to move the frames from the position which they occupy when they are actuating the control means to run the driving means, grooves in said friction rolls, said loops occupying a retracted position within the grooves when the corresponding frame is swung from said position and occupying a position outwardly of the peripheries of said loops when the frame is in said position, whereby they permit engagement of the fabric run with the roll only when the corresponding frame is causing operation of the driving means, one end of each loop being so secured to the swinging frame that its position in relation to the friction roll is varied in response to the movement of the frame.

14. Apparatus for pulling a run of adhesively coated fabric from any one of a plurality of rolls of said fabric, comprising friction rolls adapted frictionally to engage each fabric run, driving means to rotate said friction rolls, a plurality of swinging frames each adapted to be engaged by a run of the fabric as it leaves a friction roll and to swing in response to tension cast upon said run, control means actuatable by the movement of any of the swinging frames in order to start and stop the driving means, and elements to engage each of the runs upon which tension is not cast in order to hold these runs out of engagement with the corresponding friction roll, said elements being connected to the swinging frames to vary their positions in response to the movement of the corresponding frame.

15. Apparatus for pulling a run of adhesively coated fabric from any one of a plurality of rolls of said fabric, comprising a friction roll adapted frictionally to engage each fabric run, driving means to rotate said friction roll, a plurality of swinging frames each adapted to be engaged by a run of the fabric as it leaves the friction roll and to swing in response to tension cast upon said run, common control means actuatable by the movement of any of the swinging frames in order to start and stop the driving means, and elements to engage each of the runs upon which tension is not cast in order to hold these runs out of engagement with the friction roll, said elements being connected to the swinging frames to vary their positions in response to the movement of the corresponding frame, said elements also tending yieldably to move the frames against the initial tension of the fabric run.

Signed by me at Boston, Massachusetts, this 9th day of January, 1928.

HORACE M. EATON.
